UNITED STATES PATENT OFFICE.

JEAN DELWICHE, OF NEW YORK, N. Y.

GAS-HEATED FURNACE.

Application filed February 2, 1927. Serial No. 165,435.

The present invention is concerned with the provision of improvements in furnaces, particularly with an arrangement of parts which permits the ready conversion of an ordinary coal burning furnace into a gas burning furnace.

In most furnaces not specially equipped for burning gas, the introduction of a gas heating apparatus involves suitable difficulty, and ordinarily proves very unsatisfactory. The present invention provides an extremely simple gas burning equipment which may be readily applied to the ordinary furnace without necessitating any changes whatever in the usual furnace construction, or any expensive alterations. The apparatus is so arranged that the hot circulating air may be instantaneously heated if desired by substantially the entire heat transferring surface of the fire box as opposed to the usual methods which involve the production of hot spots in certain sections of the fire box walls, while leaving the other heat transmitting walls substantially cold.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a view in vertical section through a hot air heating furnace of the ordinary coal burning type showing the furnace converted in accordance with the present invention.

Fig. 2 is a transverse sectional view on the line 2—2 of Fig. 1.

While I have shown the invention applied to a hot air furnace, it will be obvious that it may be associated with a furnace in which steam, hot water or other circulating mediums are used.

In the drawings I have used the reference numeral 10 to designate the fire box of a furnace, this fire box being spaced from the outer shell 11 and cooperatively defining therewith side air spaces 12 and an upper air space 13 from which hot air is conducted by various pipes 14 to different localities where it is used for heating purposes. Ordinarily the up-draft of air through the air spaces 12, 13 enters through a screen or foraminous inlet plate 15 at the rear lower

portion of chamber 12. Products of combustion from the fire box are carried off through a pipe 16, damper controlled as at 17. The usual fire door 18 permits introduction of coal into the fire box through the opening 18^a. A grate structure 19 divides the fire box from the ash pit 20 below, and ashes may be removed through the usual opening 21, ordinarily serving as a draft opening through which the air which supports combustion enters the fire box.

The construction as thus far described, may be in every respect conventional, the present invention being more particularly concerned with the provision of novel means for converting a coal-burning furnace of any conventional type into a gas burning furnace.

To accomplish this result, I lay a plate 19^a on top of the grate 19 and cover this plate with a mound of ashes 22. The ashes are piled comparatively deep and preferably heaped up into the general pyramidal form shown. The pile of ashes materially reduces the capacity of the fire box 10, and the ashes and the plate cooperatively prevent any passage of air upwardly through the grate 19.

A mixture of gas and air is conducted into the furnace through a pipe 25 controlled by a suitable valve 26; this pipe entering the ash pit 20 through the opening 21, passing upwardly through the plate 19^a, and having its discharge end projecting for a slight distance above the apex of the ash heap 22.

The combustible gas, such for instance as ordinary natural gas or producer gas introduced through the pipe 25, is maintained at a comparatively low pressure, and the gas as it discharges from the upper end of this pipe impinges upon a spreading conical deflector 28. Member 28 may be carried if desired by supporting arms 29 on a bushing 30 screwed on to the upper end of the pipe 25.

Preferably the upper surface of the ash heap 22 is covered with asbestos or similar material, the asbestos being arranged in a series of overlapping segmental sheets 31 which may be conveniently introduced through the fire door 18 at the time the installation is effected.

In operation, no air enters the fire box 10 except the air which has already been mixed with the gas and the air which may leak through the fire door 18. The gas, due to

the fact that it is introduced under low pressure, and the further fact that it is spread by the cone 28, does not serve to 5 instantaneously heat a single spot in the upper heat transferring wall of the fire box, but distributes its heat over a wide area of the upper and side heat transferring walls, assuring a heat which may be intense; but which is in all events uniform and readily 10 controllable.

Obviously, various changes and alterations might be made in the general form and arrangement of the parts described without departing from the invention. Hence I do 15 not wish to limit myself to the details set forth, but shall consider myself at liberty to make such changes and alterations as fairly

fall within the spirit and scope of the appended claim.

I claim:

A furnace including an inner shell defining a fire box and an outer shell cooperating with the inner shell to provide a heating space, a grate structure in the fire box, a mound of ashes heaped on the grate 25 to prevent up-draft through the grate, a gas pipe including a delivery end projecting upwardly above the top of the ash mound, and overlapping segmental sheets of asbestos or the like covering the upper surface of the ash mound and leaving a central opening for the 30 gas pipe.

JEAN DELWICHE.
